CLAIM

I claim the ornamental design for a combined vegetable masher and meat scrambler, as shown and described.

DESCRIPTION

FIG. 1 is a perspective view of the combined vegetable masher and meat scrambler representing at a first end a meat cutter defined by a tapered open end of the partial cylinder and at a second end a grid defining a potato masher;

FIG. 2 is a right side elevational view of the combined vegetable masher and meat scrambler, a left side elevational view being exactly the same;

FIG. 3 is a bottom view of the combined vegetable masher and meat scrambler showing the grid across the second end of the partial cylinder;

FIG. 4 is a top view of the combined vegetable masher and meat scrambler observing directly the meat cutter at the first end of the device; and,

FIG. 5 is a perspective view of a second embodiment of the combined vegetable masher and meat scrambler indicative of indefinite length of the device.
